(57) **CLAIM**

The ornamental design for the compact sliding exercise device, as shown.

DESCRIPTION

FIG. 1 is a top plan view of a design for a compact sliding exercise device;

FIG. 2 is a bottom plan view thereof;

FIG. 3 is a right side elevational view thereof;

FIG. 4 is a left side elevational view thereof;

FIG. 5 is a rear elevational view thereof;

FIG. 6 is a front elevational view thereof;

FIG. 7 is a perspective view thereof;

FIG. 8 is a perspective view of a modified design for the compact sliding exercise device;

FIG. 9 is a right side elevational view of a design for a compact sliding exercise device with a curved bottom surface;

FIG. 10 is a left side elevational view thereof;

FIG. 11 is a rear elevational view thereof;

FIG. 12 is a front elevational view thereof;

FIG. 13 is a top plan view thereof; and,

FIG. 14 is a bottom plan view thereof.
